UNITED STATES PATENT OFFICE.

JOHN WALTER THOMAS, OF DAISY, TENNESSEE.

DIE AND SPIRAL.

1,338,799.

Specification of Letters Patent.

Patented May 4, 1920.

Application filed November 2, 1918. Serial No. 260,808.

To all whom it may concern:

Be it known that I, JOHN WALTER THOMAS, a citizen of the United States, and resident of Daisy, Tennessee, have invented certain 5 new and useful Improvements in Dies and Spirals, of which the following is a specification.

This invention relates to improvements in a die and spiral, used in connection with a 10 machine for forming clay tower spirals, and has for its object a die which is arranged adjustably and in the same is rotatably mounted a spiral which forms the inner wall of the cylinder of clay which is passed 15 through the die under pressure.

This invention is used in conjunction with a 20 machine which is the invention of Benjamin Mifflin Hood, who has made application for patent on the mechanical construction and operation of the machine to which my improved die and spiral is connected, and which die and spiral is illustrated on the drawings of the application of Benjamin Mifflin Hood, but only to illustrate the 25 operation.

As stated in the application for patent of Benjamin Mifflin Hood he does not describe nor claim the die and spiral, as this is my portion of the invention and that Hood and 30 myself are associated together in the manufacture and handling the clay tower product.

The essential feature of part of my invention is to construct a die which is attached to the front end of the clay handling machine, this die being arranged to support cylinders of various diameters and lengths and can be properly adjusted to center the same in relation with opening of 40 the die frame. And in this cylinder is rotatably mounted a spiral which forms an integral spiral wall or partition on the inner surface of a cylinder of clay and the rotation of the spiral is set at such speed to 45 properly form the spiral partition during the outward movement of the body of clay through the cylinder without fracturing or breaking the partition.

Figure 1, is a front elevation of my 50 proved die.

Fig. 2, is a central horizontal sectional view of the same.

Fig. 3, is a vertical sectional view taken on the line 3-3 of Fig. 1.

Fig. 4, is a side view of the spiral made use of.

Fig. 5, is an end view of the same.

Fig. 6, is a perspective view of the spiral.

Fig. 7, is a perspective view of one of the manufactured tower spirals or finished product 60 made by my invention.

Fig. 8, is a central sectional view of the same.

Referring to the drawings in detail 9 indicates a die frame which is supported to 65 the front end of a clay handling machine. This frame terminates into an extension 10 which is provided with a flange or wall 11. By this wall a circular recess or depression 12 is formed and in which is located the 70 adjustable die plate 13. This plate has a central opening 14, which is of a size to accommodate the insertion of a cylinder 15, which cylinder acts as the former for the outer portion or wall of the product. The 75 inner surface of this may be either straight or corrugated as that shown on the product and indicated by the numeral 16. The under surface of the die plate is provided with a cylinder recess 17 which is arranged 80 to receive the flange or shoulder 18 formed on the base of the cylinder 15. This holds the cylinder in position between the die plate and the base of the die frame. The die plate together with the cylinder located 85 therein is properly centered in relation with the opening 19 of the die frame by means of a plurality of adjusting set screws 20, located at equal intervals apart and the plate 90 13 is locked within the frame and held from being pushed outwardly by the clay pressure as it passes through the cylinder by a plurality of clamps 21, contacting with the outer face of the plate and held firmly against the outer face of the die frame by 95 cap screws 22. A clear illustration of this structure is shown in Fig. 1.

The spiral which operates in conjunction with the die and which forms the spiral inner wall of the product consists of a head 100 23 shaped in spiral form and is provided with an internally screw-threaded bore 24 to which the same is firmly attached to the stud 25, which stud in turn is attached to the inner hollow shaft 26 which operates in the 105 outer hollow shaft 27. The shaft mechanism being the invention of my associate Benjamin Mifflin Hood.

The spiral is so situated and located in the die so that its surface 28 is in alignment with 110 the base or surface 29 of the die frame and the same is of such diameter as to allow a

space 30 between the outer periphery of the spiral and the inner surface of the cylinder, which is of such thickness to form the wall 31 of the finished product; and the spiral 5 formation of the head during its rotation in the cylinder as the clay is being pressed forwardly forms the inner spiral partition 32 of the finished product.

The conical shaped recesses 33, formed in 10 the die frame and which terminates into the cylinder at the front end is supplied with the plastic clay by means of the conveyers 34. These conveyers have a tendency to press the clay forwardly at a certain speed 15 and as the clay is being forced into the cylinder, the spiral which is rotated causes the clay to pass out in the form of a cylinder with an internal spiral partition, and is in the form as that shown in Figs. 7 and 8. 20 In Fig. 3, I show the die with the clay formation as it passes through and in contact with the spiral. This clay I indicate by the numeral 35.

This device when operated in conjunction 25 with the machine mechanism passes the conveyor shaft and the shaft operating the spiral at different speeds so as to operate in conjunction with the movement of the clay under pressure.

30 Having fully described my invention what I claim is:

1. A die and spiral used for making clay tower spirals, a die frame, a flange extension formed on one end thereof, comprising 35 an adjustable die plate seated therein, a die located in said die plate, a spiral rotatably mounted in the die which is rotated through the clay and passed through the die under pressure, and during the rotation forming 40 a cylinder of clay provided with a spiral inner partition, substantially as specified.

2. A device of the character described comprising a die frame having an aperture, a die plate adjustably mounted thereon, a

cylinder supported by the die plate in 45 proper relation with the aperture, a spiral head rotatably mounted in the cylinder, the same when rotating through clay passing it through the die under pressure forms a hollow cylinder with an integral spiral wall, 50 substantially as specified.

3. A device of the character described comprising a die frame having a flange extension, die plates mounted in the flanged extension, means for centering the die plate 55 on the frame in proper relation with the openings formed therein, means for locking the plate in adjusted position, a cylinder supported by the die plate through which plastic clay is to be passed under pressure, 60 and a spiral head rotatably mounted within the cylinder for forming the clay into a cylinder with a continuous spiral partition on the inner surface, substantially as specified.

4. A device of the character described comprising a die frame attached to the forward end of a clay handling machine, adjustable die plates carried by the die frame, screws for centering the plates in 70 proper relation with the opening in the die frame, a cylinder supported by the die plate, locking plates carried by the die frame and contacting with the die plates for supporting the same and holding the plates in rigid 75 position, a spiral head located in the cylinders and rotated at a speed different from the speed of the moving clay by which a continuous spiral is formed on the inner surface of a clay cylinder passing through the 80 die, substantially as specified.

In testimony whereof, I have signed my name to this specification, in presence of two subscribing witnesses.

JOHN WALTER THOMAS.

Witnesses:

W. A. ALEXANDER,
C. C. LOVELADY.
